(57) **CLAIM**

The ornamental design for a two-way radio wrist watch, as shown and described.

DESCRIPTION

FIG. 1 is a front, right side view of the two-way radio wrist watch (Device) with upright antenna (perpendicular to face); FIG. 2 is a front view of the Device with recumbent antenna (horizontal to face);

FIG. 3 is a top and front view of the Device with upright antenna;

FIG. 4 is a right side view of the Device with upright antenna;

FIG. 5 is a left side view of the Device with recumbent antenna; and,

FIG. 6 is a rear view of the Device.

The wristband has been shown in different positions throughout the views to illustrate the adjustable nature thereof.
